PAGE 2

Fig.2

Fig.3

Fig. 4

FIGURE 1 is a right front perspective view of a combined dry cleaning machine and drier embodying my new design;

FIGURE 2 is a top elevational view thereof;

FIGURE 3 is a side elevational view thereof; and

FIGURE 4 is a left front perspective view thereof.

The dominant features of my design reside in the portions shown in full line.

It is to be understood that the pattern partially shown in broken lines are intended to cover the entire respective panel surfaces.

I claim:

The ornamental design for a combined dry cleaning machine and drier, as shown and described.
